ABSTRACT

An overall building system consisting of field-assembled, precast components, reinforcing means embedded within site-poured concrete that forms portions of the wall and floor surfaces of the building, with the reinforcing means serving to structurally unite the precast concrete components with the site-poured concrete and support the same against tension forces, shear forces, and lateral shafting forces.

The precast components include vertical load bearing walls each having vertical voids from top to bottom therein, building slabs preferable of half and full thickness adapted to span the bearing walls and receive reinforcing means thereon as well as concrete, precast stairs, an elevator module for each floor of the building, reinforcing means for tension, shear, and lateral shifting prevention purposes, and site-poured concrete first filling the voids of the load bearing wall and then serving as a floor covering for the slabs.

BUILDING FORMED OF CAST VERTICAL AND HORIZONTAL MEMBERS

RELATED APPLICATIONS

In Dillon U.S. Pat. No. 3,662,506, there was disclosed an arrangement wherein precast bearing walls were united with half thickness floor slabs through the medium of angular reinforcing and site-poured concrete.

In the presently pending application of Thomas J. Dillon on "Pre-Assembled Utility Module" filed May 12, 1971, and identified as Ser. No. 144,526, now abandoned and made the subject of a continuation application filed May 23, 1973, as Ser. No. 363,191 there was disclosed a pre-assembled utility core that was provided on a building slab and contained a bath and kitchen and eating area that was ready to use upon field positioning and connection.

In the presently pending application of Thomas J. Dillon on "Combined Elevator Shaft and Utility Module" filed May 12, 1971, as Ser. No. 142,644, now abandoned and made the subject of continuation application filed Apr. 13, 1973, as Ser. No. 351,016 there was disclosed a precast, concrete elevator floor module that was designed to be progressively stacked one on top of the other for the purpose of building the requisite elevator shaft concurrently with the erection of the building.

BACKGROUND OF THE INVENTION

The invention relates to the field of building construction either for dwelling or commercial operation in either single story or multi-story nature.

It further relates to the incorporation of a precast building operation into a field erection that is accompanied by field positioning of reinforcing means, followed by embedding the same within and on top of the precast components that have been erected.

DESCRIPTION OF THE PRIOR ART

It is believed that Dillon U.S. Pat. 3,662,506 constitutes the best prior art against the present invention.

SUMMARY OF THE INVENTION

It has been discovered that a new and total building concept can be achieved by improving the basic concepts set forth in the aforesaid U.S. Dillon Pat. No. 3,662,506.

Specifically, it has been found that if the utility module disclosed in the aforesaid pending U.S. application, Ser. No. 142,526 is modified by providing the same with horizontally projecting reinforcing means, the same can be tied in to the floor slabs shown in Dillon U.S. Pat. No. 3,662,506 to thus preclude any lateral shifting between the "heart module" shown in the pending application and the floor slab shown in the aforementioned patent.

Further, in this regard, by establishing a careful relationship in thickness between the two, the heart module slab, upon being properly positioned, serves as a natural "form" for the site-poured concrete.

Additionally, it has been found that if the elevator modules are provided with vertical voids therein, the same can be structurally innovated with the remaining components of the overall building, and thus the elevator shafts that result will be structurally united with the

building instead of being supported independently thereof as is the normal building procedure.

Finally, it has been found that if the walls are poured separately from the time the floor is poured, this will permit improved placement of the reinforcing means so that additional forces against tension, shear, and seismic forces, as well as forces against lateral shifting, can all be positioned prior to the time the floor is poured in the field.

10 It has also been found that by utilizing a system of this type, it is possible to use other precast elements such as precast corridor walls and precast balcony slabs, with all of these essential components being tied together in the final pouring of the floor as the building progresses upwardly floor by floor.

15 It has also been discovered that erecting a building in the manner that will hereinafter be described produces an additional advantage in that a high degree of safety is present to the workmen that are involved since at all 20 times during construction they are provided with a solid surface upon which to stand, with the use of scaffolding of the conventional type being avoided throughout construction.

25 Production of a totally new and innovative building concept system of the type above described is the principal object of this invention, with other objects of the invention becoming more apparent upon a reading of the following specification, considered and interpreted in the light of the accompanying drawings.

30 Of the drawings:

FIG. 1 is an isometric view partially broken away and in section and illustrating the overall concept of the system.

35 FIG. 1A is a perspective view similar to FIG. 1 but taken from a different angle and showing the structure just below the floor level of the floor that is immediately thereabove.

FIG. 2 is a similar isometric view but partially exploded for the purpose of clarity.

40 FIGS. 3, 4, and 5 are further perspective views, with FIG. 3 illustrating the condition of the component parts after positioning, while FIG. 4 illustrates the positioning of the shear dowels, tensioning steel, and reinforcing steel. FIG. 5 shows the completed product broken away and in section for clarity.

45 FIG. 6 is a similar perspective view partially broken away in section and showing the manner in which the corridor beams, heart module, floor truss slabs, and balcony slabs are positioned with regard to a typical bearing wall.

FIGS. 7 and 7A comprise a plan view using match lines A-B to show a typical floor of a building built according to the system of this invention.

55 FIG. 8 is a sectional view taken on the lines 8-8 of FIG. 7.

FIGS. 9, 9A, and 9B are floor plans of a typical one bedroom unit (9), a typical one bedroom end unit (9A), and a typical efficiency unit (9B).

60 FIGS. 10 and 10A comprise a plan view using match lines A-B to show a foundation plan of the building shown in FIG. 7.

FIGS. 11 and 12 are sectional views taken on the lines 11-11 and 12-12 of FIG. 10.

65 FIGS. 13 and 13A comprise a plan view using match lines A-B to show a structural floor plan showing the position of the roof components of the building illustrated in FIG. 6.

FIGS. 15, 16, and 17 are sectional views taken on the lines 15—15, 16—16, and 17—17 of FIG. 13A.

FIGS. 18, 19, 20, and 21 are sectional views taken on the lines 18—18, 19—19, 20—20, and 21—21 of FIG. 13.

FIGS. 22, 23, and 24 are sectional views taken on the lines 22—22, 23—23, and 24—24, respectively, of FIG. 14.

FIG. 25 is a sectional view taken on the line 25—25 of FIG. 13.

FIGS. 26, 27, and 28 are sectional views taken on the lines 26—26, 27—27, and 28—28 of FIG. 13A.

FIGS. 29, 30, 31, and 32 are sectional views taken on the lines 29—29, 30—30, 31—31, and 32—32 of FIG. 13.

FIG. 33 is a plan view of the stabilizer used to initially secure the bearing wall with respect to the heart module.

FIG. 34 is a side elevation view thereof.

FIG. 35 is a perspective view of the brace used to temporarily secure the bearing wall with respect to the floor upon which the same is received.

FIG. 36 is a view showing in detail the clamping mechanism.

FIG. 37 is a partial plan view of a modified form of the corridor wall construction.

FIG. 38 is a section taken on the lines 38—38 of FIG. 37.

FIG. 39 is a plan view of a typical elevator module.

FIGS. 40, 41, 42, and 43 are sectional views taken on the lines 40—40, 41—41, 42—42, and 43—43, respectively, of FIG. 39.

FIG. 44 is an elevational view of a typical end wall member identified in co-related drawings as EW-1.

FIGS. 45 and 46 are top and bottom views thereof.

FIG. 47 is an elevational view of a bearing wall identified in co-related drawings as BW-1.

FIGS. 48 and 49 are top and bottom views thereof.

FIG. 50 is a plan view of the heart module slab referred to in co-related drawings as HME-1L.

FIG. 51 is a side view thereof.

FIG. 52 is a plan view of the floor truss slab hereinafter referred to in co-related drawings as FTS-1.

FIG. 53 is an elevational view thereof.

FIG. 54 is a plan view of a corridor truss span herein-after referred to in co-related drawings as CTS-1.

FIG. 55 is an elevational view thereof.

FIG. 56 is a plan view of the balcony slab hereinafter referred to in co-related drawings as BS-1.

FIG. 57 is an elevational view thereof.

FIGS. 58 and 59 are plan and elevational views of a precast stair landing referred to in co-related drawings as SL-1.

FIG. 60 is a typical end detailed for such precast stair landing.

FIG. 61 is a section taken on the lines 61—61 of FIG. 13A and showing the stairs installed.

GENERAL DESCRIPTION OF THE SYSTEM

A general understanding of the system can thus be had by reference to the above-identified Dillon U.S. Pat. No. 3,662,506 and the presently pending application of Thomas J. Dillon on "Pre-Assembled Utility Module" and "Combined Elevator Shaft and Utility

Module" filed May 12, 1971, and May 12, 1971, respectively, and respectively identified as Ser. No. 142,526 and Ser. No. 142,644.

In Dillon U.S. Pat. No. 3,662,506, a general description of the system is set forth, and essentially it is shown there how there is a combined use of precast concrete and site-poured concrete to achieve a monolithic structure that has reinforcing means embedded within the site-poured concrete following erection and placement 10 of the precast components at the building site.

For clarity in this general description portion of the specification, the principal components of the system will be referred to by their initials. Thus the bearing walls shown in FIGS. 1 and 1A, for example, are identified 15 by the letters BW. Similarly, the floor truss slabs will be identified by the letters FTS, while the heart module and elevator module will be indicated by the letters HM and EM, respectively. Similar additional abbreviations will be utilized for the remaining components, with site-poured concrete being identified as SPC for example (see FIGS. 3 and 5).

Because of structural limitations, it is often times necessary to vary the size of the basic components involved. Thus on certain of the drawings, such as FIGS. 13 and 13A and FIGS. 14 and 14A, it will be observed that there may appear such diverse designations as FTS-1, FTS-2. This merely indicates a different configuration and dimension of the floor truss slab in plan view.

30 In addition to being identified by the initials involved, each major component is separately described, and in such instances the specific description will be undertaken with the conventional numerals in all instances.

35 Also, as has been noted above, certain figures, namely, FIGS. 7, 10, 13, and 14, do not lend themselves to being placed on a single sheet. For these reasons, these are designated as FIGS. 7 and 7A, with match lines A,B being shown on each sheet to indicate 40 the match point of the two drawings.

SPECIFIC DESCRIPTION OF THE SYSTEM

A. FOUNDATION MEANS

45 Although it is apparent that any one of several conventional foundation means could be employed, the embodiment of the invention shown in the accompanying drawings envisions the use of the so-called "caisson" type of foundation which is best illustrated in FIGS. 10, 10A, and 15 through 31 of the drawings.

50 Referring to FIG. 10, a typical series of caissons 100, 101, 102, 103, 104, and 105 are positioned in a line so as to support a grade beam 106, for example, with similar grade beams 107, 107a, and others that are not numbered being utilized for the purpose of providing a foundation surface that is elevated above grade level as shown in FIGS. 15 through 23.

55 Referring to FIG. 15, the grade beam 108 shown therein includes the usual reinforcing means 110 that extends downwardly within the confines of the caisson 111 in this instance as shown in broken lines.

60 Referring next to FIG. 16, a concrete footer 112 positioned on the grade beam 113 serves as a perimeter wall for field-poured concrete 114. Similarly, and as shown in FIG. 17, this same grade beam could support the opposed ends of a heart module HM positioned in the notched portion thereof as clearly indicated at FIG. 65 17.

By the use of this arrangement, the first floor of the building will be comprised, prior to pouring, of heart modules, elevator module, and footers that are supported on grade beams. In this regard it is to be noted that the ends of adjacent heart modules, for example, are slightly spaced apart from each other (see FIG. 20) so that a reinforcing shear dowel 116 can project upwardly. By this arrangement when the first bearing wall 117 is positioned, there will be a void within which the concrete being received in the upper portion thereof during pouring of the second floor can be received, and this will serve to unite bearing wall 117 with respect to the heart modules as shown in FIG. 20.

A similar arrangement exists with respect to the field-poured concrete 114 that is shown in FIG. 19 of the drawings. It is to be understood with reference to FIG. 19 that the field-poured concrete 114 could, of course, partially be replaced by precast slabs much in the manner the remaining floors are completed.

B. DESCRIPTION OF PRECAST COMPONENTS

1. Bearing Walls (BW)

The bearing walls (BW) are best shown in FIGS. 47, 48, and 49 of the drawings.

As will be noted therefrom, each bearing wall is of slab-like configuration so as to include opposed faces 120,120a, opposed ends 121a,121b, as well as a top surface 122, and a bottom surface 123. A plurality of vertical square voids 124,124 extend from the top surface 122 to the bottom surface 123, and it will be noted from the top and bottom views that wire mesh 125 and 126 is positioned on opposed sides of the voids for structural strength purposes during the making of the bearing walls.

Lifting loops 127,127a are provided in the top surface 122 for permitting lifting of these units at the building site as by crane.

Preferably a pair of additional reinforcing rods 128,128 are provided, with one of these rods being positioned on each side of the vertical voids in close proximity to the bottom surface 123. In use, a nominal width of eight inches is recommended, although it is to be understood that the greater or lesser widths and structural strengths could be utilized if conditions so dictated.

2. Heart Modules (HM)

While the heart module is described in detail in the co-pending application of Thomas J. Dillon filed May 12, 1971, and identified as Ser. No. 142,526 and entitled "Pre-Assembled Utility Module" which contains a full and complete description of the heart module concept, certain additional structural data relative to the slab portion thereof appears in FIGS. 50 and 51 of the drawings to which reference is now made.

Also, the physical layout of the heart module (HM) is shown in the detail drawings of FIGS. 9, 9A, and 9B.

The plan view of the heart module slab (HMS) illustrated in FIG. 50 shows a generally rectangular block-like member having a plurality of reinforcing rods 130,130 that extend transversely thereof, with one end 130a thereof projecting beyond the opposed edges 131,131 of the heart slab module so that the same may be moved to the chain-dotted line position following positioning on the bearing walls in the field.

It will also be noted that a pair of through voids 132 and 133 are provided between the top surface 134 and

the bottom surface 135 thereof, with these voids providing a built-in utility chase within the confines of the module. Wire strand lifting loops 136,136 project from the opposed longitudinal end walls 137 and 138, and it will be noted that these lifting loops 136 are spaced closer to the top surface 134 than they are to the bottom surface 135, with the same also being true with regard to the projecting ends 130a of the reinforcing rods 130,130. This arrangement is to permit them to be bent

out over an adjacent slab or building component that was of half thickness size compared to the thickness of the heart module slab which is normally eight inches and is referred to as a "full thickness" slab. Each of the voids 132,133 has additional reinforcing rods 139,139 around the perimeter thereof and in embedded condition for structural strength.

3. Floor Truss Slabs (FTS)

While the heart module slabs just described in connection with FIGS. 50 and 51 have been designated as

20 "full thickness," the floor truss slab shown in FIGS. 52 and 53 is "half thickness" so that when it is placed in transverse abutment with a heart module slab, the members 130a thereof can be folded out and lie above the top surface 140 of the adjacent floor truss slab, as best shown in FIG. 1, for example.

The floor truss slabs are again rectangular in plan and include a top surface 140, a bottom surface 141, opposed side surfaces 142 and 143, and end surfaces 144 and 145.

30 Reinforcing means 146,146 are internally embedded throughout the length of the floor truss slab for structural strength, and also the top surface 140 is preferably raked so as to be rough as indicated in the area designated by the numeral 140a.

35 Four wire strand lifting loops are also embedded within the slab as indicated by the numerals 147,147 and the projecting portions 147a,147a thereof are provided adjacent each corner of the slab so that a uniform lift may be made without difficulty for erection purposes at the building site.

4. Balcony Slabs (BS)

The construction of the balcony slab (BS) shown in FIGS. 1 and 1A is described in detail in FIGS. 56 and 57 of the drawings to which reference is now made.

45 It will be first noted that the balcony slabs are "full thickness" so that when they are positioned next to the just described floor truss slabs, as shown in FIGS. 1 and 6, for example, the top surface 151 thereof will be elevated above the top surface of the adjacent floor truss slab, which will be "half thickness" as already described. It will further be noted that this surface 151, as shown in FIG. 57, slopes slightly from rear edge 152 toward the front end 152b for drainage purposes, and it will further be noted that the opposed ends 153 and 154 are provided with notches or offsets 152a and 153a so that the forward portions will jut beyond the point of support by the bearing wall that is positioned beneath the balcony slab in supporting relationship therewith.

55 60 A series of inserts 155,155 are cast into the upper surface 151 of the slab for the purpose of installing the balcony (B) in known fashion, and furthermore lifting inserts 156,156 are provided for field insertion of lifting rings for erection purposes.

In addition to the aforementioned component parts, each balcony includes a series of reinforcing rods 157,157 that project beyond the wall 152 so that the

same may be moved to the dotted-line position shown at 156 following positioning in the field, with these extended reinforcing rods then being embedded within the site-poured concrete (SPC) that is poured on top of the adjacent floor truss slab. Additional reinforcing rods 158,158 are also shown provided in embedded condition beneath the surface 151 as clearly shown in FIGS. 56 and 57 of the drawings. A notch 159a is provided in the lower surface 159 for preventing water from dripping onto the porch below.

Each lateral edge has a curb 152c provided thereon for supporting the next bearing wall in the most efficient manner and for preventing the ingress of rain into the dwelling unit.

The heart module slab (HMS) and the balcony slab (BS) can also be referred to as "perimeter slabs" since they define the inner and outer perimeter of each building bay, with the lateral perimeters being defined by the bearing walls (BW).

5. Corridor Truss Slab (CTS) and Corridor Beam (CB)

The construction of the corridor portion of the dwelling unit is best shown in FIGS. 6, 13A, 26, 27, and 28, and first referencing to FIG. 6, it will be noted that when the bearing walls have been positioned, there is a space between the same that defines the corridor area of the building as noted in FIG. 6. This space is spanned by a pair of angle members 160,160 that are known as "corridor beams," with the opposed edges of the corridor beams resting on the opposed ends of the bearing walls as shown in FIG. 6.

The corridor truss slab (CTS) is then positioned on the legs of the corridor beams 160,160 so as to define the corridor area of the building. Normally and as shown in FIG. 6, the corridor truss slabs will be the first horizontal units positioned following erection of the bearing walls, with this being preferred because it enables the building to be accurately located, and in view of the fact that the modules are sequentially positioned outwardly from the corridor, so to speak, so as to cause the building to grow in width in a progressive fashion, with the heart module first being positioned, following by positioning of the two floor truss slabs and finally positioning of the balcony slab, as clearly shown in FIG. 6 of the drawings.

Again it will be noted that the corridor truss slabs are "half thickness" compared to the heart module slabs, with it being noted that the reinforcing members projecting from the heart modules can then be embedded within the field-poured concrete at the time the floor of the building in question is being finished off (see FIGS. 27 and 28).

A typical corridor truss slab is shown in FIGS. 54 and 55 and is identified as CTS-3, with the location of this being identified in the structural plan of FIG. 13.

As will be noted, the unit is generally rectangular in plan except that it includes a cutout portion 161 for a combination of the elevator module and a second cutout portion 161a that is intended to accommodate the utility chase 162 shown in FIGS. 7 and 13 of the drawings. In addition to the usual wire mesh 163 that is employed in the construction of this type, there are transversely extending reinforcing bars 164,164 provided at various positions both at the end and intermediate length thereof as clearly shown in FIGS. 54 and 55, with the diagonal bracings 165,165 being provided adjacent the inside corridors for reinforcing purposes.

Again, and as in the case of the floor truss slab, the top surface 166 is raked rough as indicated at the numeral 167, and also as in the case of the floor truss spans (FTS), a plurality of wire strand lifting loops 168,168 are provided adjacent the four corners, with it being noted that the same may be readily folded down and covered when the corridor truss span is covered with concrete during field erection.

6. End Walls (EW)

10 The construction of the end walls (EW) is shown in detail in FIGS. 44, 45, and 46 of the drawings, and further disclosure of the construction of the end wall unit in the completed stage of the building is set forth in FIGS. 15, 16, and 17 of the drawings.

15 Referring now to FIGS. 44, 45, and 46, since the end walls are bearing walls also, it is manifest that the same will have a construction similar to the construction of the bearing walls that have been previously described. Accordingly, and referring to the elevational view

20 shown in FIG. 44, the front surface 172 is provided with an offset front portion 173 that forms a ledge 173a upon which either a heart module slab, a floor truss slab, or a balcony slab may be rested as shown in FIGS. 15, 16, and 17, with this arrangement permitting access 25 to the vertical voids 174,174 that are provided in the end wall from top to bottom as clearly shown in FIGS. 45 and 46.

Wire strand lifting loops 175,175 are also provided and project from the top surface 173a as shown in FIGS. 44 and 45.

30 Each end wall also includes an extreme top surface 176, a bottom surface 177, and opposed ends 178 and 178a as clearly shown in FIG. 44, with conventional reinforcing bars 179,179 also being provided for the usual reinforcing purposes, and with reinforcing mesh 179a,179a being provided on opposed sides of the voids as clearly shown in FIGS. 45 and 46.

35 In this regard, angular reinforcing steel (ARS) may be used to stabilize the end walls or, if desired, cast-in-place hook bars may likewise be employed to provide stability, with the former method being illustrated in FIG. 16 of the drawings. A hook bar arrangement is shown in FIG. 17 of the drawings where hook 80c is cast into place around the shear dowel shown therein.

40 Use of similar reinforcing hook rods are shown in FIG. 21 where another hook rod 80d is shown cast in place so as to stabilize the heart module with respect to the end wall.

45 The frontal surface 172 may be provided with a texture or decorative surface if so desired for aesthetic purposes.

7. Elevator Module (EM)

50 The detailed construction of the elevator module is set forth in FIGS. 39 through 43 of the drawings, and its association with the remaining components of the building is set forth in FIGS. 13, 13A, 14, 14A, 22, 23, and 24 of the drawings.

55 An elevator module of this type is set forth and disclosed in the co-pending application of Thomas J. Dillon entitled "Combined Elevator Shaft and Utility Module" and filed May 12, 1971, and now pending as Ser. No. 142,644. Reference is made to the disclosure of said application which has been listed as a related application earlier in this specification.

60 Referring first to the plan view of the elevator module shown in FIG. 39, it will be noted that the elevator shown is a two-elevator unit having a front surface 180,

a rear surface 181, and opposed side surfaces 182 and 183, with door openings 184,184a being provided in the front wall 180 for ingress and egress purposes and with the usual elevator doors 185,185a opening and closing with respect to the door openings at the proper time to permit the entry and discharge of passengers from the elevator units which are shown outlined in chain-dotted lines in FIG. 39 and as indicated by the letter E.

As in the case of the bearing walls (BW) and end walls (EW), the elevator module (EM) preferably includes a series of vertical voids within which the site-poured concrete (SPC) may be received.

Referring now to FIGS. 40 and 41, it will be noted that each end wall 182 and 183 has leveling pockets 186,186 provided therein on the lower edge 187 thereof, with these leveling pockets cooperating with shim means (not shown) that will be placed on the embedded brackets 188,188 that are embedded in the top wall 189 of the elevator module. This leveling action is described in detail in related application, Ser. No. 142,644 above-noted, and it will not be repeated herein.

Referring again to FIG. 40, it will be noted that both the front and rear walls are provided with embedded plate members 190,190, with these plates serving as a point of support for attachment of the I-beam members 191,191 that are employed for the purpose of supporting elevator guide rail brackets 192,192 that in turn support the vertical elevator guide rails 193,193.

As noted in FIG. 39, the interior faces of the end walls 182 and 183 support the remaining guide rollers 194,194 that will be used to guide each of the two elevators shown, with FIG. 41 illustrating how the guide rail supports 195,195 are secured with respect to the interior of the wall for supporting the guide rails 194,194, with the same guide rails preferably also supporting the conduit member 196 within which the electrical components may be housed. A limit switch 197 is normally provided at ground floor level only for controlling the descent of the elevator beyond this point.

Referring now to FIG. 43, it will be noted that the inside surface of the rear wall 181 also supports a counter-weight guide rail and brackets that are indicated generally by the numeral 198, with the usual counter-weight 199 (see FIG. 39) being encased therein and moving upward and downward in conventional fashion.

Referring now to FIG. 42 for a further description of the elevator door mechanisms, it will be noted first that a pair of spring door closing mechanisms 200,200 are provided for each door, with motor interlocks 201,201 preventing opening of the doors until such time as the motor roller release assembly 202 has been properly positioned to indicate that the door can be safely opened.

The usual guide rails 203, 203 are provided in each instance to permit the door to freely move into and out of closed position upon operation of the usual control 204.

Notches 205,205 extend transversely of each end wall 182 and 183 for the purpose of coacting with the heart modules that are shown disposed adjacent thereto in FIG. 14 of the drawings.

In this regard the position of the elevator modules in stacked or assembled condition is shown best in FIGS.

11 and 12 of the drawings where this feature is clearly illustrated, with the heart module received within the notch 205 so as to be supported on the top edge 189 of the elevator module immediately beneath the one shown in FIG. 11.

With regard to the assembly of the elevator module after positioning, the wall voids 180a,180a are filled and the shear dowels (SD) positioned therein (see FIGS. 11 and 12) in a manner similar to erection of the bearing and end walls, with the floor being subsequently poured as shown in FIG. 23 and with reinforced rod 80b being used in known fashion.

One of the advantages of the invention is that assembly can essentially be completed prior to lifting of the module into place. This permits much of the time-consuming work to be done on the ground in advance of being lifted into erection position, and by this arrangement it has been found that the elevator can be dropped into the top of the elevator shaft very shortly after placing of the last elevator module in place. This, in effect, materially reduces the overall construction time considerably.

8. Stair Landings (SL)

The precast stair landings (SL) shown in FIGS. 1 and 1A of the drawings are shown in detail in FIGS. 58, 59, and 60 of the drawings, while FIG. 61 of the drawings shows the manner in which the stair landing is structurally united with the remaining components of the building during construction.

Referring first to FIG. 61, it will be noted that the stair system employed is what is generally referred to as a "scissors" system, which means that there are two flights of stairs between each floor level with an intermediate landing being provided.

Each precast stair landing includes a stair portion 210, an upper landing portion 211, and a lower landing portion 212, with the usual reinforcing mesh 213 being embedded therein both adjacent the top and bottom surfaces of the stair landing unit. Additionally, lifting rings 214,214 are provided at each end for the purpose of lifting the entire unit into place during erection. It will be further noted that pockets 215,215 are provided in each end, with a stud anchor 216 being received in each pocket to provide additional support when the unit is placed in position during erection.

Regarding erection and positioning of the unit, reference is now made to FIG. 61 of the drawings wherein the unit has been shown positioned, with one end being supported on a corridor truss span (CTS) and the other end being shown supported on one side of an end wall (EW). By this arrangement when the field-poured concrete, indicated in FIG. 61 by the numeral 217, is poured both on top of the corridor truss slabs (CTS) and end wall (EW), concrete will be made level with the landing surfaces as shown in FIG. 61, following which conventional railings 218 can be installed.

While a description has been given in accordance with a so-called scissor type set of stairs, reference is made to FIG. 2 of the drawings wherein a conventional single flight of stairs is shown being positioned in the stair opening shown therein.

9. Roof Corridor Truss Spans (RCTS), Roof Truss Slabs (RTS), Roof Balcony Slabs (RBS), and Roof Heart Module Slabs (RHMS)

The roof framing plan is shown in FIGS. 14 and 14A of the drawings. Since the roof of the building in question is essentially no different than any remaining por-

tion of the building, a detailed description of the individual roof elements will not be undertaken.

Suffice it to say that the roof members, in general, correspond to their counterparts on the other floors of the building.

Thus a roof corridor truss slab is in reality no different than a normal corridor truss span of the type previously described in detail. It again is "half thickness" as are the roof truss slabs that have been identified as RTS.

Similarly, the roof balcony slabs are, as in the case of the normal balcony slabs, "full thickness." When all parts are positioned as shown in FIG. 1, they will form the border to which the concrete will be poured. The only other "full thickness" slab on the roof is the roof heart module slabs (RHMS) that are positioned on opposite sides of the elevator module as shown in FIG. 14.

In this regard a detailed construction of the roof members can be noted in FIGS. 15 through 23 of the drawings where decking D and roofing R are shown utilized in known fashion to enclose the building.

C. NON-PRECAST COMPONENTS

1. Reinforcing Steel

Although the majority of the precast components above-described have reinforcing means provided therein at the time of delivery to the building site, several different types of reinforcing means are field-positioned and subsequently embedded within the structure during the field pouring of concrete in a manner that will now be described.

In this regard reference is first made to FIG. 4 of the drawings wherein the general arrangement of positioning the reinforcing means is most clearly illustrated. Again, abbreviations will be used to designate the component parts.

In each instance of use, shear dowels (SD) are positioned within the vertical voids 124,124 of the bearing wall (BW) (FIGS. 18, 19, 20, and 21) in the manner shown in FIGS. 4 and 5, as well as in the vertical voids 174,174 of the end wall (FIGS. 15, 16, and 17) and the vertical voids 180a,180a of the elevator module (FIGS. 22 and 23).

In this regard, and in each instance referring to the above-noted drawings, the shear dowel is positioned in the void after the same has been partially filled with concrete in the field, and the shear dowel is generally approximately four foot in length so that two feet will be inserted within the bearing wall, end wall, or elevator module wall that has been filled with field-poured concrete, while two feet will project above the same much in the manner shown in FIG. 5 of the drawings wherein the field-poured concrete has been poured to the floor level.

When the next bearing wall is positioned on top of the floor surface for erection of a subsequent floor, the part of the shear dowels that are projecting in FIG. 5 will ultimately be covered and embedded within concrete poured within the voids of the subsequently positioned bearing wall.

Also utilized in each instance is conventional reinforcing mesh (RM) which is laid over the exposed surfaces of the positioned floor truss spans (FTS) as shown in FIG. 5. Said mesh would also be employed over the top of the corridor truss spans (CTS) which are not shown in either FIGS. 4 or 5. This mesh is ultimately

embedded beneath the surface of the floor that is poured in the field.

Additionally and as shown in FIGS. 4 and 5, field-positioned tension steel (TS) is employed by being positioned over the mesh so as to interconnect adjacent floor truss slabs in the manner shown in FIG. 4 of the drawings. Tension steel is generally of bar stock and serves to provide a tension force between adjacent living units.

10 Referring next to FIG. 21 as a typical example, it will be noted that there is also provided an angular reinforcing steel (ARS) that is used in the roof section of the building, with this member ultimately being embedded within the concrete poured on the roof portion of the building, with one leg being inserted in the voids of the bearing wall, end wall, or elevator module as the case may be.

15 Referring next to FIGS. 13A and 16, it will be noted that provision is made in all end bays to avoid what is known as "progressive collapse" which means that a failure of one floor results in the subsequent failure of additional lower floors. Thus and referring to FIG. 13A, if an explosion force in the direction of arrow X should result in failure of the end wall indicated, the additional steel indicated by the letters PCS, which is the abbreviation for progressive collapsed steel, would serve to still support the wall in cantilever fashion off of the bearing wall, and it will be noted from FIG. 16 that the progressive collapsed steel (PCS) is angled in position within the voids of the bearing wall so as to provide this additional force that would prevent "progressive collapse."

20 Additional support against progressive collapse is made through the use of structural studs 310 shown in FIG. 1A of the drawings.

25 It has already been noted with regard to the heart module slabs (FIGS. 50 and 51) and the balcony slabs (FIGS. 56 and 57) that the same have reinforcing rods 30 that are intended to be bent in the field so as to overlie the floor truss slabs and corridor truss slabs to permit the same to be covered with the concrete that is poured in the field to further strengthen the tie between them.

35 45 As shown in FIG. 6, it is sometimes desirous to eliminate these projections and use an "all thread" type of reinforcing rod that is merely threaded into inserts provided in the heart module or balcony slab, with these merely being threaded rods that would be embedded within the concrete much in the manner of the reinforcing means shown in FIGS. 50, 51, 56, and 57.

50 50 "All thread" rods are illustrated schematically by the numeral 300,300 in FIG. 6 of the drawings.

55 In certain areas having a high incidence of earthquakes and ground tremors, provision is made for the use of seismic steel in addition to the conventional shear dowels (SD) previously described. Seismic steel is long length bar stock (e.g. 10 ft.) that is again inserted within the voids of the bearing wall much in the manner that the shear dowels are inserted. However, the seismic steel is joined end-to-end throughout the height of the building as by cadwelding, threading, or like means, to provide a continuous, unbroken rod.

60 65 In instances where seismic steel is used, the same will normally be used in a ten foot length, with the bearing wall being slipped down over the projecting portion thereof, and with the same again being embedded

within concrete much in the manner that the shear dowels are embedded.

Also, in certain areas of the building, such as the community areas on the first floor which span several bays, it will be necessary to use something other than a bearing wall in this area. In such instances and as shown in FIGS. 29 through 32, metal spans, either in the form of I-beams or angles, are supported at their opposed ends and, in turn, support the floor truss spans, with dowels of the type shown therein being used to mix with the site-poured concrete shown.

2. Penthouse (P)

The penthouse unit (P) is shown best in FIG. 8 of the drawings where it will be noted that the same is a steel framed building positioned on top of the uppermost elevator module (EM) so that the equipment required to operate the elevators can be housed therein. The construction thereof employs the conventional framing elements, and no invention per se is claimed with respect to the penthouse (P) which is merely made to house the equipment required to operate the elevators.

3. Typical Floor Plans

A typical floor plan is shown in FIGS. 7 and 7A of the drawings, with match lines A,B being provided on these drawings to show the point of match between the two sheets of drawings.

As will be seen from FIGS. 7 and 7A, each floor includes stair landings SL-1 and SL-2, as well as an elevator module as shown in FIG. 7. In the plan shown in FIG. 7, each floor is essentially made up of one-bedroom units, with the end one-bedroom units being designated by the numeral E-1BR, the conventional one-bedroom units being designated by the numeral 1BR, and the efficiency units being designated by the numeral E. A laundry (L) shown in FIG. 7 is located on one or more floors of the building, while one or more utility chases (UC) are provided on each floor for reception of conventional conduits, trash disposal, and the like.

Referring now to FIG. 9 wherein a typical one-bedroom unit is illustrated, it will be noted that the same includes a bath area 225, a kitchen area 226, a corridor entry 227, storage 228, living room 229, and bedroom 230. It will be further noted that the perimeter portion of the building is enclosed in this instance by a curtain wall 231 that is non load bearing in nature and includes sliding doors 232,233, as well as a unit 234 that can be used for heating and air conditioning purposes. A balcony 235 having a railing 236 completes the arrangement shown in FIG. 9.

Referring now to FIG. 9A, there is illustrated a typical one-bedroom end unit that includes a corridor entry door 240, kitchen 241, bath 242, storage area 243, living area 244, and bedroom area 245, with partitions 246 separating the living room and bedroom areas, while curtain wall 247 and balcony 248 complete the living arrangements.

The efficiency unit shown in FIG. 9B includes a corridor entry door 250, a kitchen area 251, bath area 252, and a combined living/sleeping area 253, with curtain wall 254 separating the living area 253 from the balcony 255.

D. ERECTION TECHNIQUES

During the erection of the high-rise, certain techniques are preferably employed to achieve the most satisfactory results, and these techniques will now be

described in connection with the overall description of the invention.

1. Shoring

Because the corridor truss slabs and floor truss slabs are "half thickness" in size, it is necessary to shore or prop up these units until such time as the topping has been poured on the same and hardened into place. Shoring merely involves the providing of transverse support beneath the slab and adjusting it to the proper level so that the same will not sag as would otherwise be the case. No drawing is believed required to explain this well-known technique, but it is important to note that the floor truss slabs and corridor truss slabs must be shored up until such time as the same have been covered with concrete and allowed to harden.

2. Stabilizing

Because of the relatively large size of the bearing walls, it is preferable to brace stabilize the same until the same are finally filled with the reinforcing means and field-poured concrete. To this end, certain means for stabilizing and bracing are shown in FIGS. 1, and 33 through 35 of the drawings. The stabilizer 260, illustrated in FIGS. 33 and 34 of the drawings, includes a thin plate member that is offset as at 261 and provided with a first hole 262 as well as additional holes 263,263 that are provided in the opposite end thereof, with the holes 263,263 being adapted to permit attachment to the roof of a heart module as shown in FIG. 1, while the holes 262 can be secured to an appropriate pin provided on the bearing wall for this purpose.

FIGS. 35 and 36 show a bracing arrangement that has been employed for the purpose of bracing the bearing wall against wind until such time as the same can be stabilized with respect to the heart module and other components. The bracing means shown in FIG. 35 include an angle iron 270 having a hole provided at one end therein for insertion around a pin 271 that is provided on the outer edge of the balcony slab (BS) shown in FIG. 35. A C-clamp 272 has an arm 273 pivotally secured thereto, with the arm 273 being connected to a turnbuckle 274 whose opposed end is secured to the plate 270 as shown in FIG. 35 of the drawings. By this arrangement the bearing wall (BW) can be accurately braced with respect to the balcony slabs until the same can be permanently stabilized as by the field pouring of the concrete therein.

3. Seismic Modification

FIGS. 37 and 38 show a modification utilized in high-rise seismic zones. In this arrangement the corridor walls 280 are made of similar construction to the bearing walls shown, so that when the voids 281,281 thereof are poured with concrete as shown in FIG. 38, the same will not only support the corridor truss slabs, but will also be united structurally with the bearing walls.

E. ERECTION PROCEDURE

Although much of the erection procedure and technique has been set forth in the foregoing detailed description of component parts, a sequential step-by-step recitation of the erection steps will now be discussed in detail.

1. Site Preparation And Completion Of Foundation Means

Before any of the precast components can be positioned, it is, of course, necessary to first have the foundation properly prepared. Included in this operation will, of course, be the site preparation to the extent

necessary to accommodate sewers, water, and other utilities along with proper grading.

During this preparation and referring to FIG. 10, the first physical objects installed are the caissons, such as the caissons 100 to 105 shown in FIGS. 10 and 10A of the drawings, with such caissons first being driven to the appropriate depth and then filled with concrete and reinforcing rods in the fashion shown best in FIGS. 15 to 23.

As shown in these figures and also in FIGS. 10 and 10A, grade beams, such as grade beams 107a, 107, are supported on the caissons for the purpose of supporting heart module units between parallel adjacent grade beams, with a typical heart module being positioned initially as shown in FIG. 10 in chain-dotted lines spanning the space between the parallel grade beams 106 and 107.

The final step in preparing the foundation is the pouring of the frost walls 109, 109a, 109b, 109c (FIG. 10), and 109d and 109e (FIG. 10A), and any remaining frost walls for the non load bearing walls of the building.

When this operation has been completed, the enclosed portion of the building is provided with the appropriate gravel which is then compacted to obtain the density needed to provide sub-surface to the concrete that will subsequently be poured.

2. The First Floor

At this time and with work completed on the foundation, erection of the first floor of the building is commenced by first positioning the heart modules in spanning relationship to the grade beams, much in the manner as illustrated in FIG. 10 of the drawings.

It will also be noted from FIGS. 11 and 12 that the elevator module pit (EMP) has been located on the caissons that support the same, and at this time the first floor elevator module (EM) can be positioned thereon as clearly shown in FIGS. 11 and 12.

It will also be assumed that during the preparation of the foundation the reinforcing rods, such as the rod 275 shown in FIG. 21, have been positioned, and at this time it is merely necessary to pour the site-poured concrete (SPC) floor to the level of the ground floor elevation as defined by the top of the positioned heart module slab (HMS).

When the concrete floor surface of the first floor of the building has set to the requisite degree of hardness, the bearing walls (BW) for the first floor may be positioned over the upwardly projecting rods 275,275 using the bracing means shown in FIGS. 35 and 36 to position these members in place and, further, stabilizing the same to the roof of the heart modules (HM) much in the manner shown in FIG. 1 by use of the stabilizer 260 shown in FIGS. 1, 33, and 34.

As soon as the bearing walls for the first floor have been positioned as just described, the second floor elevator will be placed, and following this the corridor beams 160,160 will be positioned on the inboard ends of the spaced-apart bearing walls (BW) as shown in FIG. 6, for example, and then secured in place.

Following this, the corridor truss slabs (CTS) will be positioned in spanning relationship between adjacent corridor beams 160,160 so that a temporary center portion of the building now exists, with it being noted that as earlier mentioned, the building will grow outwardly from side-to-side hereinafter.

Again referring to FIG. 6, the heart modules (HM) are positioned on opposed sides of the corridor truss span (CTS), with normal procedure being to position all heart modules (HM) first along the corridor, followed by positioning of the floor truss slabs (FTS) and the balcony slabs (BS) in that order until the building has grown outwardly to its full width.

As mentioned earlier, the all-thread bolts 300 shown in FIG. 6 will be positioned or, alternatively, the reinforcing rods 130,130 shown in FIGS. 50 and 56 will be bent outwardly so as to be disposed in a position above the surface of the corridor and floor truss slabs (CTS, FTS) but beneath the final finish floor level, which is represented by the top surface of the heart module slab (HMS) and the top surface of the balcony slab (BS).

During the period that the ceiling of the first floor is being completed, the second floor elevator module (EM) has been installed on top of the first floor elevator module, and also during this same period when the various slabs (HMS, CTS, FTS, BS) are being positioned to form the floor of the second floor of the building, the precast stair landings SL-1 and SL-2 can be installed in the manner previously described in connection with FIGS. 58 through 61, with this condition being schematically illustrated in part in FIG. 1 of the drawings.

All slabs to receive structural topping are shored at mid-point of their span. Shoring heights are adjusted so the bottom of the slabs match that of the adjacent heart module slabs (HMS) and balcony slabs (BS).

When all of the components have been positioned as just described, the dwelling will have an appearance substantially similar to that shown in FIGS. 1, 13, and 13A, and at this time the next step will be to pour the vertical voids of the bearing walls (BW), the end walls (EW), and the elevator module (EM) for the first floor.

One point that should be observed with respect to the positioning of the just described walls is that the same are normally shimmed so as to be spaced approximately one-half of an inch off of the floor surface upon which the same are supported. This is done for the reason that it permits the gravitationally descending concrete within the voids of the bearing and end walls to force out the air and thus avoid any voids, with it being possible to observe the emitting concrete on the floor level below that on which the pour is being made. Normally these shims are of asbestos material and also serve the dual purpose of permitting very fine adjustment as to leveling, etc.

Preferably the concrete is poured in the voids of these vertical walls to about a point two or three inches beneath the top surface thereof. At this time and after appropriate hardening has taken place within the voids, the shear dowels (SD) are inserted to a depth of about two feet within the concrete that has just been poured within the voids of the bearing wall (BW), end wall (EW), and elevator module (EM) (see FIGS. 16 to 23).

Also at this time the tension steel (TS) is placed over the voids in a horizontal mode, and also the reinforcing mesh (RM) is positioned over the floor truss slabs (FTS), corridor truss slabs (CTS) and also over the top of the vertical voids that have just been poured with concrete.

At this time site-poured concrete (SPC) can be poured over the floor truss slab (FTS) and corridor

truss slabs (CTS) and the vertical voids filled, floated, and otherwise raised to the level of the balcony slabs (BS) and heart module slabs (HMS) so as to produce a finished floor.

When the second floor portion of the second floor of the unit has been completed to the extent just described, the sequence of events would then be repeated by first positioning the bearing walls (BW) thereon, followed by installation of the third floor corridor beams 160 and the corridor truss slabs (CTS) which are positioned on the beams. Following this, installation of the third floor heart module (HM), elevator module (EM), floor truss slabs (FTS), and balcony slab (BS) may be done, with this process being repeated until the roof portion of the building has been completed.

During work upwardly on the building, at each floor the precast stairs SL-1 and SL-2 and elevator modules (EM) are progressively inserted as the building progresses so that when the building is topped out, the stairs and elevator portion of the building are substantially completed, having been fitted with hardware as the work progressed upwardly.

Accordingly, it is merely necessary to lift the entire elevator cab unit by crane into the elevator shaft, and following appropriate blocking and shoring of the same within the shaft, the elevator penthouse can be placed over the elevator shaft, and the equipment therein attached to the elevator for operation substantially coincident with the topping out of the building.

Also to be noted is the fact that as the building progresses from floor to floor, the plumbing and electrical and other work can be done concurrently therewith, with the plumbing wall of the heart module being readily accessible as set forth in more detail in the co-pending application of Thomas J. Dillon, Ser. No. 142,526 filed May 12, 1971, and entitled "Pre-Assembled Utility Module."

Also it will be noted that as each floor progresses, workmen can commence work to complete the floor, with this work including such items as positioning of the curtain wall, installing partitions, hanging doors, putting on balcony railings, connecting plumbing, electrical, and heating outlets, and generally readying the units for occupancy.

MODIFICATION

The modified form of the invention shown in FIGS. 37 and 38 of the drawings essentially follows the same technique of erection that has just been described, with the single exception that the corridor bearing walls 280, having voids 281,281, are employed and are also filled at the same time as the remaining voids of the bearing walls, the end walls, and elevator module in the manner just described.

As shown in FIG. 37, the use of these units will require heart module slabs having central voids 302,302 instead of the side voids shown in FIG. 50 of the drawings.

CONCLUSION

It will be seen from the foregoing that there has been produced a new and unique total building system that constitutes an innovative marriage between precast components, reinforcing steel, and site-poured concrete to achieve an extremely strong, highly unitized building that is capable of being erected in minimal time and with minimal expense.

While a specific order of erection has been set forth specifically in the preceding paragraphs, it follows that delivery delays and other delays may necessitate the procedure being somewhat interrupted and taken out of turn. However, the overall procedure generally follows the steps of first pouring the vertical walls, then positioning the horizontal slabs, followed by pouring of a floor surface.

It will also be noted that added safety to the workmen 10 is another advantage of this invention since at all times during construction the workmen have solid surface upon which to perform their duties. There never exists a situation where they are working on scaffolding or other temporary structures of this nature, and thus an 15 additional degree of safety is present.

While a full and complete description of the invention has been set forth in accordance with the dictates of the Patent Statutes, the invention is not intended to be limited to the specific form recited herein.

Accordingly modifications of the invention may be resorted to without departing from the spirit hereof or the scope of the appended claims.

What is claimed is:

1. A unitized building of the character described, comprising:

A. precast concrete components including

1. vertical load bearing walls arranged in pairs and in parallel relationship with each other to form a building bay having a length dimension and a width dimension, with each said bearing wall having a series of vertical voids extending from top to bottom internally thereof;

2. parallelly arranged floor truss slabs that are horizontally positioned between inner and outer perimeter slabs of substantially greater thickness in parallel spanning relationship to the width dimension of each said bay;

3. said floor truss slabs and said perimeter slabs being supported, in laterally abutted relationship, on the facing longitudinal edges of one pair of said bearing walls in non-covering relationship with the voids thereof;

B. shear dowels received in said vertical voids of vertically adjacent bearing walls;

C. tension steel horizontally spanning said vertical voids and being positioned on the upper faces of said floor truss slabs in adjacent building bays whereby said tension steel will prevent said longitudinally adjacent floor truss slabs from shifting relatively of each other;

D. lateral steel positioned over said floor truss slabs beneath the uppermost surface of said perimeter slabs and extending transversely therefrom for co-action with a transversely adjacent floor truss slab;

E. site-poured concrete filling said vertical voids and covering said tension steel, the central portion of said shear dowels, said lateral steel, and covering said floor truss slabs to the height of said perimeter slabs whereby the floor portion of each floor of said building is formed.

2. The building of claim 1 wherein one said perimeter slab has a utility core structure secured thereto to define a heart module.

3. The building of claim 1 further characterized by the presence of corridor slabs that span the space between longitudinally adjacent building bays.

4. The building of claim 3 wherein said perimeter slabs have removable projecting reinforcing means that overlie the surface of adjacent floor truss slabs and corridor slabs; said site-poured concrete covering said reinforcing means.
5. The building of claim 4 wherein said perimeter slabs are full thickness and said floor truss slabs and said corridor truss slabs are half thickness.
6. The building of claim 1 further characterized by the presence of precast stair units that are structurally interconnected to said precast concrete components of successive floors.
7. The building of claim 1 further characterized by the presence of an elevator module having a plurality of vertical through voids in the walls thereof structurally interconnected to said precast components of successive floors by said site-poured concrete filling said vertical voids of said elevator modules on each floor.
8. A partially "precast" and partially "cast in place" building that includes a plurality of separate dwelling units of the character described, comprising:
- A. foundation means;
  - B. a series of precast, vertically positionable bearing walls arranged in parallel relationship with each other to form a building bay, with each bearing wall having a series of vertical voids located centrally thereof and extending from top to bottom of said walls;
  - C. a series of elongated, precast floor truss slabs each spanning the space between adjacent said bearing walls and each being supported at their longitudinal ends by the outer edge portion of said bearing walls, whereby said voids of said walls are accessible following positioning of said floor topping slabs on said bearing walls;
  - D. a series of precast heart modules each
    - 1. spanning the space between adjacent bearing walls whereby the same can be supported thereon
    - 2. having a thickness approximately twice the thickness of each said floor truss slabs,
    - 3. supported on the edge portions of said bearing walls in spaced-apart relationship with each other, whereby said voids of said bearing walls are accessible, and
    - 4. being arranged equi-distant from the center line of the corridor portion of said building;
  - E. corridor beams transversely spanning the space between said heart module and being supported on the longitudinal ends of said bearing walls;
  - F. precast corridor sections supported at their opposed ends on said corridor beams and having a thickness approximating a thickness of said floor topping slabs;
  - G. stair portions vertically interconnecting successive corridors of adjacent floors;
  - H. a series of non load-bearing walls spanning the

- space between parallel load-bearing walls in right angle relationship therewith for dwelling unit closure purposes, with said non load-bearing walls defining opposed perimeter portions of said building;
- I. opposed precast vertically arranged load-bearing end walls arranged in parallel relationship with said first mentioned load-bearing walls and defining opposed perimeter portions of said building;
- J. roof means covering the uppermost series of dwelling units and enclosing said building to the elements;
- K. first site-positioned reinforcing means positioned in vertically aligned relationship within the voids of vertically adjacent load bearing walls following site pouring of concrete;
- L. second field-positioning means horizontally disposed on top of horizontally adjacent floor topping and corridor slabs and being embedded within said site-poured concrete beneath the floor surface thereof on each floor;
- M. third site-positioned reinforcing means projecting from the floor portion of each said heart module and extending over the surface of said corridor topping slabs, said floor topping slabs, and said bearing walls whereby the same will be embedded beneath the floor surface of each said floor following site pouring of said concrete;
- N. balcony slabs corresponding in approximate thickness to the thickness of the slab portion of said heart module, with said balcony slabs being supported on their opposed ends by said bearing walls in side-by-side parallel relationship with said floor topping slabs;
- O. fourth field-positioned reinforcing means projecting laterally from one edge of said balcony slab in overlying relationship with the adjacent floor topping slab whereby the same will be embedded within said field-positioned concrete;
- P. site-poured concrete at each floor level of said building poured
1. over said field-positioned floor topping slabs and said corridor slabs to the floor surface level of said heart module and said balcony slabs whereby
- a. a floor surface is created,
  - b. said voids of said bearing walls are gravitationally filled, and
  - c. said first, second, third, and fourth mentioned reinforcing means are embedded beneath the floor surface of said site-poured concrete;
- Q. said site-poured concrete structurally integrating said load-bearing walls, said floor topping slabs, said heart modules, said corridor slabs, and said balcony slabs into a monolithic floor surface for each floor of the building.
